UNITED STATES PATENT OFFICE.

JACOB H. WEISBROD, OF ST. LOUIS, MISSOURI, ASSIGNOR TO AMERICAN CAR & FOUNDRY COMPANY, OF ST. LOUIS, MISSOURI, A CORPORATION OF NEW JERSEY.

BRACE FOR CAR-WALLS.

No. 831,315.

Specification of Letters Patent.

Patented Sept. 18, 1906.

Application filed March 28, 1906. Serial No. 308,489.

To all whom it may concern:

Be it known that I, JACOB H. WEISBROD, a citizen of the United States, residing at St. Louis, Missouri, have invented a certain new and useful Improvement in Braces for Car-Walls, of which the following is a full, clear, and exact description, such as will enable others skilled in the art to which it appertains to make and use the same, reference being had to the accompanying drawings, forming part of this specification, in which—

Figure 1 is a side elevation of a portion of a car-wall provided with a plurality of braces embodying the features of my invention. Fig. 2 is a transverse sectional view taken at a point indicated by the line 2 2 of Fig. 1; and Fig. 3 is a view similar to Fig. 1, showing my improved braces arranged in a slightly different manner.

This invention relates to cars, and particularly to freight-cars of the type known as "gondola" cars.

The object of my invention is to provide novel means for bracing the sides and end walls of a car, said means consisting of a combined post and diagonal, which is preferably connected at its upper and lower ends to the top and bottom chords of the car-wall.

In the embodiment herein shown, which represents the preferred form of my invention, I have shown my combined post and diagonal as being formed by an angle; but it should be understood that other well-known commercially-rolled shapes capable of being provided with a sharp bend could be used without departing from the scope of my invention.

Referring to Fig. 1 of the drawings, 1 designates the side wall of a car provided at its upper edge with an angle 2, acting as the top chord, and at its lower edge with an angle 3, acting as the bottom chord. A brace consisting of a combined post 4 and diagonal 5, formed by bending a continuous L-shaped bar into the form of an acute angle, is connected to the top and bottom chords of the wall. The lower end of the post is bent at approximately a right angle to the body portion thereof, and the lower end of the diag-

nal is also bent slightly, so that the opposite ends of the brace will lie parallel to the horizontal leg of the angle 3 at the lower edge of the car-wall, rivets 6 passing through the bent portions of the brace and through the vertical leg of the angle 3. The upper end of the brace at the point where the post and diagonal merge is connected to the vertical leg of the angle 2 at the upper edge of the wall by rivets 7. Preferably and as herein shown a plurality of these braces are provided for the car-wall, said braces being so arranged that the end of the deflected portion of a post abuts against the end of the deflected portion of the diagonal of the adjacent brace. A construction of this character very effectively braces the wall of a car and prevents the central portion of the wall from sagging, the top and bottom chords of the wall being rigidly connected together by said braces.

In Fig. 3 I have shown a slightly-modified form of my invention, wherein the opposite ends of the brace are connected to the angle at the upper edge of the car-wall, the portion of the brace where the post and diagonal merge being connected to the angle at the lower edge of the car-wall.

Having thus described the invention, what is claimed as new, and desired to be secured by Letters Patent, is—

1. A car-wall brace comprising a combined post and diagonal formed from a continuous piece of flanged metal, the free ends of said piece of metal being bent at an angle to the body portions thereof; substantially as described.

2. A car having a wall provided with top and bottom chords, and a plurality of braces connected to said chords, said braces comprising continuous flanged members bent to form posts and diagonals, having their free ends deflected and butting against each other; substantially as described.

3. A car having a wall provided with top and bottom chords, and a plurality of braces connected to said chords, said braces being formed by bending continuous pieces of metal of the same shape in cross-section

throughout their length so that they constitute combined posts and diagonals, the free ends of said posts and diagonals being bent at an angle to the body portions thereof, and
5. the end of one post abutting the end of an adjacent diagonal; substantially as described.
In testimony whereof I hereunto affix my

signature, in the presence of two witnesses,
this 26th day of March, 1906.

JACOB H. WEISBROD.
